Primary Examiner — Sandra Snapp*Assistant Examiner* — Ieisha Price(74) *Attorney, Agent, or Firm* — Pillsbury Winthrop Shaw Pittman LLP(57) **CLAIM**

The ornamental design for a helmet visor screw, as shown and described.

DESCRIPTION

FIG. 1 is a perspective view of a helmet visor screw showing our new design;

FIG. 2 is a top plan view thereof;

FIG. 3 is a side elevation view thereof;

FIG. 4 is a bottom view thereof; and,

FIG. 5 is a sectional side elevation view thereof, taken at line 5-5 of FIG. 2.

The broken lines in the drawings illustrate portions of the helmet visor screw and form no part of the claimed design.

1 Claim, 3 Drawing Sheets(56)
